UNITED STATES PATENT OFFICE

153,237

DESIGN FOR A CONDIMENT RECEPTACLE

James R. Scheip, Tipp City, Ohio, assignor to
H. H. Chaffee, J. A. Scheip, and J. R. Scheip, a partnership doing business as Safety Corner
Company, Tipp City, Ohio

Application April 14, 1947, Serial No. 138,365

Term of patent 7 years

(Cl. D44—10)

To all whom it may concern:

Be it known that I, James R. Scheip, a citizen of the United States, residing at Tipp City, in the county of Miami and State of Ohio, have invented a new, original, and ornamental Design for a Condiment Receptacle, of which the following is a specification, reference being had to the accompanying drawings, forming a part thereof, wherein:

Fig. 4 is a plan view thereof.

I claim:

The ornamental design for a condiment receptacle, substantially as shown.

JAMES R. SCHEIP.
